SYNCHRONIZING METHOD AND APPARATUS

Stewart L. Clothier, Irvington, and Harold C. Hogencamp, Maplewood, N. J., assignors to Kolorama Laboratories, Inc., Newark, N. J., a corporation of New Jersey

Application September 27, 1937, Serial No. 165,794

4 Claims. (Cl. 178—7.1)

This invention relates to television and more particularly to a method and apparatus for generating synchronizing impulses at the proper line scanning frequency.

5 In television systems it is essential that the scanning rate of both the transmitter and the receiver be properly synchronized in order to obtain satisfactory operation. By means of the present apparatus the scanning line frequency is 10 maintained between receiver and transmitter through the use of synchronizing impulses which are imposed upon the electrical fluctuations emanating from the transmitting station. For example, when the television signals are transmitted by radio, separate synchronizing impulses are imposed upon the carrier preferably in intervals between the successive line scans. The synchronizing impulses are employed at the receiving station to regulate the frequency of the scanning lines, and may also be used at the transmitting station to regulate the operation of a monitoring device.

The objects of the present invention are: to provide an improved scanning line synchronizer 25 which may be employed at a television transmitting station to synchronize the frequency of a cathode ray scanner employed either in the transmitting or in the receiving apparatus; to provide a means for synchronizing the scanning 30 line frequency of a mechanical television receiver; and to provide means for adjusting the position of the scanning line synchronizer so as to obtain horizontal framing of the picture. These and other objects of the present invention will 35 become more readily apparent from the following description and from the appended drawing disclosing a preferred form of apparatus for practicing the present invention.

In the drawing:

40 Fig. 1 is a diagrammatic view of a mechanical transmitter adapted for scanning motion picture film showing the manner in which the scanning line synchronizer is arranged in conjunction with a scanning drum;

45 Fig. 2 is a detailed elevational view of the synchronizer showing the manner of mounting the synchronizing photocell;

Fig. 3 is an end view of the synchronizer shown in Fig. 2; and

50 Fig. 4 is a cross-sectional view of a synchronized mechanical scanner.

The invention is particularly adapted for use with a mechanical transmitter of the type employing a mirror drum, as herein disclosed and 55 described, in which case the mirror drum may

be utilized for both the television scanning and the scanning line synchronizer. A typical arrangement embodying such an apparatus is illustrated in Fig. 1 and comprises a scanning drum 11 rotated at the desired rate by means of 5 a constant speed motor 12. The drum 11 is provided about its periphery with a plurality of plane reflecting surfaces 13 preferably normal to the face of the drum 11. When employed for scanning motion picture film, the drum is employed in conjunction with a source of high intensity illumination such as an arc light 14 which is adapted to concentrate a beam of light B through a condensing lens 15 onto a transverse elongated area of a film F which is moved 10 longitudinally at a constant rate of speed by means of sprockets 16. The portion of the film illuminated by the beam B is controlled by the shape of a slot 17 formed in a mask 18 positioned closely adjacent to the film F. The beam 15 after penetrating the film F is focussed by means of a projection lens 19 so that successive images I of the illuminated slot 17 are formed 20 in the plane of an aperture plate 21 after being reflected from successive surfaces 13 of the drum 11. A photocell 22 is located behind the plate 21 so as to receive imposed upon its sensitive surface the elemental areas resolved from the successive images I. The responses from the photocell 22 which comprise the television images or signals are increased in amplitude by 25 means of a suitable signal amplifier 23 from which the signals are transmitted as by wire or by a radio transmitter 24 to the receiving station. The apparatus thus far described 30 comprises a mechanical television transmitter capable of scanning motion picture film, to which the present invention may be applied.

The scanning line synchronizer forming a part 40 of the present invention may be added directly to the film scanning mechanism and as shown in Fig. 1 preferably includes an exciter lamp 25 comprising a source of high intensity illumination such as an incandescent filament, and a projection lens capable of forming a concentrated beam of light B' which beam is preferably directed so as to continually strike the same surface 13 that the beam B impinges upon. The exciter lamp is adapted to form a concentrated light ray or image in the plane of the 45 synchronizer aperture plate 26.

Referring now more especially to Figs. 2 and 3, the synchronizer comprises a frame 27 secured as by means of mounting lugs 28 in fixed relation to the drum 11. The aperture plate 26 is 50 55

mounted upon the frame 27 in any convenient manner so as to admit of adjusting substantially circumferentially with respect to the drum 11. This may be accomplished as shown in Fig. 2, for example, by mounting the plate 26 within longitudinal slides 29, and the sliding motion may be regulated by means such as a threaded thumb screw 31 journaled within a boss extending from the frame 27 with the threaded stem of the screw 31 engaging a lug 32 forming a projection of the plate 26. By rotating the screw 31 the plate 26 may be moved longitudinally within the slides 29 so as to alter the position of the vertical slit or aperture 33 with respect to a fixed point on the periphery of the drum 11. A synchronizer photocell 34 is positioned behind the plate 26 so that the beam B' may strike the sensitized photo-sensitive surface of the photocell 34 after passing through the slit 33. If the desired movement of the plate 26 within the slides 29 is appreciable, it may be preferable to mount the photocell in fixed relation to the plate 26 and aperture 33 as shown in Figs. 2 and 3. Accordingly the photocell 34 socket 35 may be mounted directly and securely to the plate 26 as by means of a bracket 36. In this manner the photocell is moved in accordance with the motion of the plate 26 and the position of the photocell 34 with respect to the slit 33 is maintained constant. The responses from the photocell 34 may be amplified by means of a suitable synchronizer amplifier 37 from which the impulses may be wired to the receiving station, or if a radio transmitter is employed the synchronizer impulses may be superimposed upon the carrier modulated by the signals from the photocell 22. The impulses from the amplifier 37 may also be employed to synchronize a monitor 38 located at the transmitting station.

In operation, the aperture plate 21 is spaced from the drum 11 and the lens 19 is adjusted so that the respective images I are separated by a slight space representing a time interval between successive lines. The beam B is projected upon the plate 21 with the motor 12 stationary, and the position of the drum 11 is adjusted, preferably manually, so that the space between adjacent images I coincides with the position of the slot in the aperture plate 21. The exciter lamp 25 is then adjusted so that the beam B' strikes the periphery of the drum 11 with the beam B' reflected in the general direction of the slit 33. By means of the thumb screw 31 the plate 26 is then adjusted longitudinally until the concentrated spot or image formed by the beam B' coincides with the position of the slit 33. Accordingly at the interval between successive line scans the photocell 34 is exposed to the action of the beam B'.

When the motor 12 is set in operation and the film F is moved to obtain scanning, the photocell 22 is energized successively by the images I reflected from the surfaces 13 about the periphery of the drum 11. During the intervals that the photocell 22 is not energized, the photocell 34 receives impulses of constant intensity from the lamp 25 at a frequency coinciding with the number of line scans formed by the drum 11. The impulses from the photocell 34 are suitably amplified and they may be employed to synchronize the operation of a monitor 38 by establishing the operating frequency or they may be employed in a similar manner to synchronize

the operation of a television receiver by means of wire or radio transmission.

If the monitor or receiver employs a cathode ray tube, the synchronizing impulses are utilized to synchronize the usual sweep-circuit oscillator employed to provide the necessary deflection voltage, in a manner well known in the art.

As shown in Fig. 4, the synchronizing impulses may be employed to synchronize a mechanical receiving scanning mechanism of the type employing a rapidly rotating disc or drum similar to that employed at the transmitter if the principal power employed in rotating the drum is supplied from an outside source in such a manner that the drum rotates substantially at the synchronized speed.

The power is transmitted from a conventional motor through a shaft 39 to a rotatable phonic wheel 41 comprising a magnetizable disc, the periphery of which is provided with a plurality of spaced teeth 42, equal in number to the number of surfaces about the periphery of the scanning drum 11', which drum is secured firmly to the shaft 39. The synchronizing impulses are carried through wires 43 and 44 to coils 45 mounted upon a core 46. The speed control is effected by the intermittent magnetic attraction between poles 47 and the respective teeth 42. If the energizing impulses for exciting the coils 45 are transmitted with the television signals they are filtered out and amplified in the usual manner.

Manipulation of the thumb screw 31 advances or retards the synchronizing impulses of the photocell 34 depending upon the direction of movement of the plate 26. This movement is operative to properly frame the picture, in its line scan dimension.

The lamp 25 is shown projecting the beam B' upon the same surface that the beam B is projected upon. In this manner greater precision in the synchronizer is obtained since all error caused by angular inaccuracies of the respective surfaces 13 is eliminated. It is to be understood, however, that if the drum is constructed with a high degree of precision, the beam B' may be projected upon any other of the surfaces 13.

Although the apparatus shown in Fig. 1 comprises a complete mechanical television transmitter the portion of the apparatus comprising the drum 11, the scanning line synchronizer S and the amplifier 37 may be employed in conjunction with a synchronous motor 12 as a separate and complete unit to provide synchronizing impulses for a cathode ray transmitting tube. Under such circumstances the operation is very similar to the operation of the cathode ray receiver in which the amplifier 37 is used to amplify the photocell impulses from the synchronizer S to synchronize the sawtooth sweep oscillator which controls the operation of the deflecting coils forming a part of the cathode ray transmitting tube.

It will be readily apparent to those skilled in the art that the present invention may be employed in conjunction with any mechanical scanner (film, direct pickup, or flying spot) which utilizes a line scanning drum of the type shown and described herein. Other modifications and arrangements of the hereinbefore described apparatus may be made without departing from the spirit of the invention or sacrificing any of its advantages.

We claim:

1. A synchronous signal generator for use in television systems comprising the combination with a scanning drum having a plurality of reflecting surfaces about its periphery, of a substantially constant-intensity light source; means for directing a light beam from said source upon the periphery of said drum; a synchronizing photocell in the path of the light beam reflected 5 from said surfaces; an aperture plate positioned between said photocell and the periphery of said drum; and framing mechanism comprising means for adjusting the position of said plate in a direction substantially circumferentially with respect to said drum.
2. A synchronizing signal generator for use in television systems, comprising the combination with a scanning drum having a plurality of reflecting surfaces about its periphery, of a substantially constant-intensity light source; means for directing a light beam from said source upon the periphery of said drum; a synchronizing photocell in the path of the light beam reflected from said reflecting surfaces; a frame positioned 10 between said photocell and said drum; an aperture plate slidably mounted with respect to said frame; and means for adjustably positioning said aperture plate with respect to said frame.
3. In a combined television scanning apparatus and synchronizing impulse generator having a scanning drum, phasing means comprising a frame fixed with respect to said drum; an aperture plate slidably mounted with respect to said frame; means for adjustably positioning said aperture plate with respect to said frame; and a photocell secured in operative relation to 15 said aperture plate.
4. In a television apparatus, having scanning 10 mechanism comprising frame scanning means, a rotatable line-scanning mirror drum, an aperture plate, and a photocell, said scanning means and said drum being operable to project images of successive elemental areas of the object to 15 be scanned through said aperture plate upon said photocell to form the television impulses, the combination comprising a light source, means for projecting light from said source upon said mirror drum, a synchronizing photocell exposed 20 to the light successively reflected from said mirror drum to thereby form synchronizing impulses, means for combining the television impulses and said synchronizing impulses, and means for varying the phase relation between the synchronizing 25 impulses and the television impulses.
